UNITED STATES PATENT OFFICE.

GEORGE H. BURNHAM, OF LAWRENCE, MASSACHUSETTS, ASSIGNOR TO
ELIZABETH ROGERS, OF LYNN, MASSACHUSETTS.

DISPLAY-STAND.

SPECIFICATION forming part of Letters Patent No. 605,307, dated June 7, 1898.

Application filed March 17, 1897. Serial No. 627,988. (No model.)

To all whom it may concern:

Be it known that I, GEORGE H. BURNHAM, of Lawrence, in the county of Essex and State of Massachusetts, have invented certain new and useful Improvements in Display-Stands, of which the following is a description sufficiently full, clear, and exact to enable those skilled in the art to which it appertains or with which it is most nearly connected to make and use the same.

This invention has relation to display stands or holders constructed and adapted to receive and hold various small articles of apparel or wares for display in a store-window or the like and for other purposes; and it has for its object to provide a display-stand which in arrangement and construction of parts shall be of an artistic and serviceable form and adapted to receive and hold various small goods or wares in a convenient and compact form, so as to display to good advantage the qualities of the same.

The invention consists in certain new and improved features of construction and arrangement of parts, all as is hereinafter set forth in the following description, and the novel features of which are pointed out with particularity in the appended claim.

Of the drawings, Figure 1 shows in elevation my improved display-stand. Figs. 2 and 3 are details.

Referring to the drawings, A is a base or foot, which has formed therein an interiorly-threaded socket *a*, into which is fitted the threaded extremity of an upright or standard *b*. The upright or standard *b* is threaded at its upper end, and to the said threaded end is fitted an interiorly-threaded cap *c*, to which is fixed a clip *d*. At convenient intervals along its length the rod or upright *b* is tapped to receive the threaded extremities *s* of horizontal arms *e*, which are preferably constructed from lengths of wire formed of spring metal and bent up at their outer ends and formed at that point into spring-clips *e'*, consisting of two or more turns, which are preferably of the form shown in Fig. 2—that is to say, the said outer ends of the arms *e* are coiled into a spring either of the shape shown in Fig. 3 or of the triangular shape shown in Fig. 2. I prefer to form the clips of the triangular shape shown in Fig. 2, as I find in

practice that this form permits of an article being inserted between the springs more easily than is the case when the clips are formed as in Fig. 3, though sometimes this fact is not material, and the form shown in Fig. 3 may seem desirable. The upright *b* is also tapped to receive the threaded extremity of shorter arms *f*, which at their outer ends are likewise bent up and formed into clips *f'*, which are preferably arranged so as to encircle the shank portion of the arms *e* and *g*. Additional arms *f*, formed with clips *f'*, may be arranged or provided, projecting forwardly from the upright *b*. The clips *e* of the arms *e* embrace the shanks of the arms *g*.

The arrangement and construction of a display-stand such as I have described permits of a variety of artistic arrangements or groupings of goods or small wares upon the stand, the spring-clips holding or securing them firmly in place, at the same time in no way injuring or defacing said goods.

The clips formed on the arms *e*, *f*, and *g* are preferably arranged so as that they lie in a plane at right angles with the said arms in order that a collar or the like when inserted between the springs of the clips will be held or presented so as to display the same to the best advantage.

Having thus explained the nature of the invention and described a way of constructing and using the same, though without attempting to set forth all of the forms in which it may be made or all of the modes of its use, it is declared that what is claimed is—

A display-stand embracing in its construction a base, a standard extending up from the base, radial arms *e*, *f*, *g*, screwed at their inner ends into the standard and provided on their outer ends with clip-coils, the shank of the arms *e* extending through the clip of the arm *f*, and the shank of the arm *g* extending through the clips of the arms *e* and *f*, as set forth.

In testimony whereof I have signed my name to this specification, in the presence of two subscribing witnesses, this 9th day of March, A D. 1897.

GEORGE H. BURNHAM.

Witnesses:

A. W. CROSSLEY,
ARTHUR F. RANDALT.
